UNITED STATES PATENT OFFICE.

HARRY BRIDGMAN SMITH, OF BROOKLYN, NEW YORK, ASSIGNOR, BY MESNE ASSIGNMENTS, TO HOAGUE-SPRAGUE CORPORATION, OF LYNN, MASSACHUSETTS, A CORPORATION OF MASSACHUSETTS.

METHOD OF PRODUCING BOXES AND BOX BLANKS.

Application filed January 12, 1923, Serial No. 612,172. Renewed June 25, 1926.

This invention relates to methods of producing boxes in general conformity with continuous box production methods previously invented by me as disclosed in various patents and pending applications including companion applications executed on even date herewith.

The structures here disclosed are described and claimed in a divisional application Ser. No. 123,201, filed July 17, 1926.

A characteristic feature of the present invention is the connection of separate strips or webs of box body or shell material by strips of suitable material, usually paper 15 thinner than the shell material and of suitable strength and toughness, and having suitable folding qualities, these connections providing hinging or folding connections of improved and advantageous characteristics. 20 Incidental to the described connection or hinging structure and method, in some cases the shell material for the complete, continuous box blank assembly may be originally furnished or handled in the form of a single 25 roll or web, and this web may be split or cut longitudinally to separate it into a plurality of parts, and the connecting or hinging strips may then be applied to reconnect these separate parts for the purpose of forming the fold or hinge lines in an advantageous way.

An important object of such structures and production methods is that they avoid an important difficulty heretofore experienced in producing boxes, namely that in the operations of creasing or folding and bending the materials they are so deformed or strained that when the blanks are folded and secured in box form, the walls, and especially the side walls, frequently bulge in an objectionable manner, and to cure this defect, more or less elaborate and expensive means have to be adopted to remove the bulge after the box has been completed, or else various precautions or expedients have to be employed to avoid distorting or straining the materials, or to otherwise eliminate the bulge in some of the intermediate steps of production methods.

50 My invention eliminates this difficulty by eliminating the tendency of the materials to bulge. In other words by applying suitable hinge strips to separate shell members, the

stiff shell member is not distorted or strained and it therefore has little or no tendency to 55 bulge or depart from a desired flat condition in intermediate steps of the process or in the box as finally set up and fastened.

Important economies in material costs are also introduced especially when some or all 60 parts of the shell material are originally available in the form of narrow strips or rolls which may in fact be trimmings or other waste materials produced in various operations of a paper-working plant.

65 In addition to the principal distinctive features of the invention above mentioned it includes various process steps and structural features in general conformity with continuous production methods of my invention as above stated, and reference should be made to my prior patents and applications, and companion applications also 70 above referred to, for an understanding of many of the added features and variations 75 that can be incorporated in connection with the significant features of this invention, and it will be attempted herein only to explain only a few certain relatively simple box structures and methods for producing them.

80 A very important feature of the invention is of course the incorporation of its principal distinctive features above referred to in a complete continuous-production method 85 in order to realize the greatest speed and economy in box production on a commercial scale.

86 The characteristics and advantages of the invention are further sufficiently explained 90 in connection with the following detail description of the accompanying drawings, which show certain exemplifying box structures and certain representative performances of the process; and after considering these persons skilled in the art will understand that many variations may be made 95 within the principles of the invention, and I contemplate the employment of any methods or method steps which are properly within the scope of the appended claims.

100 Figure 1 is a perspective view, in diagrammatic form, of materials and mechanisms sufficiently explaining one performance of the process.

Figure 2 is a side elevation.

Figure 3 is a top plan.

Figure 4 is a bottom plan.

Figure 5 is a perspective view illustrating a modification of the method.

Figures 6, 7, 8 and 9 are fragmentary details in section, illustrating different fold formations.

Figure 10 is a perspective view of an individual blank assembly.

Figure 11 shows the same partly folded 10 into box form.

Figure 12 is a perspective view of the completed box part.

Figure 13 is a section at 13—13, Figure 12.

15 Referring first to Figure 1, a continuous strip or web 1 of suitable box body or shell material, such as card board or chip board of suitable grade and thickness, is advanced from a roll 2 over a guide roll 3. At a suitable point in its advance the web is separated into a plurality of parts, usually three parts, namely, a center strip 4, and side strips 5 which are usually of equal width and which may be wider, narrower, or of 20 the same width as the center strip, the relative dimensions of the strips depending upon the dimensions of the box part to be produced. In the present case the center strip 4 constitutes central or body portions of the 25 completed box blank and end wing portions thereof, while the side strips 5 constitute side wing and corner lap portions of the blank. The separation of the continuous web into strips is accomplished in this case 30 by rotary slitting knives 6 co-operating with an abutment roll 7.

The separate web portions are now desirably spaced apart slightly, more or less, depending on the nature of the fold or hinge 40 to be produced between the adjacent portions. A suitable spacing of the shell portions in one instance is indicated in Figure 6 where the space 8 between adjacent strips 4 and 5 is about equal to the thickness of the 45 shell material. This arrangement can be varied within considerable limits. To effect this separation or spacing of the web portions, rotary spacing wheels 9 are provided which have flanges adapted to enter between 50 adjacent edges of the strips and hold them properly apart, and of course the spacing devices may be multiplied or varied so as to maintain the strips in proper relation during subsequent operations, or at least, 55 until they are reconnected by the hinge strips. For the sake of compactness in the drawing, the separators 9 are shown quite close to the slitters 6, but of course this distance may be as great as necessary or desirable 60 to avoid any lateral distortion of the material.

To reconnect the shell strips and provide the hinge formations, strips 12 of suitable connecting and hinging material, such as 65 strong and tough paper of suitable char-

acter, for example, the kind of paper known in the trade as Kraft paper, are advanced from rolls 13 and over glue rolls 14, and are then directed under guide and pressing rolls 15 in contact with margins of the respective 70 shell strips 4 and 5, and over the spaces 8, and pressed adhesively in position on the shell material, and coincidental with this application of the hinge strips or by independent operations, the hinge material may in 75 some cases be depressed between the adjacent edges of the shell strips as clearly shown in Figure 6 where 16 indicates the depressed or beaded portion of the hinge strip 12. For this purpose a central peripheral flange 80 17 may be provided on the pressing roll 15 or the formation of this depression or bead in the hinge material may be coincidental with the formation of a similar depression in the cover paper as presently explained. 85

A continuous strip or web 20 of suitable cover material, usually paper of a desirable grade, is advanced from a roll (not shown) and over a glue roll 21 and under a pressing roll 22 where it is brought in adhesive 90 contact with the shell strips and over the hinge strips. The cover material may be depressed to form concave beads 24, Figure 6, corresponding with the depressions or beads 16 in the hinge strips, by peripheral flanges 95 25 on pressing roll 22, or at this point both the cover material and the hinging material may be depressed into the spaces between the shell strips as shown in Figure 6 without the previous depression or formation of 100 the hinge strip bead 16 as above explained.

When depressions or beads are formed in the hinge strips or cover paper, or both, as above described, from the point of their formation onward, in addition to other purposes or functions of these formations, they serve to maintain or aid in maintaining the proper spacing of the shell strips. 105

Otherwise the hinge material and the cover material, either or both, may be applied flat and smooth across the longitudinal shell spaces 8 as clearly shown in Figure 8.

Subsequent operations may vary considerably, depending on the desired box structure and other considerations. In the present particular example, wherein the cover web has laterally projecting margins 30, these margins are turned down and under and adhesively secured to under surface margins of the outer shell strips 5. At a suitable point in the advance of the combined materials transverse fold lines or creases 31 are formed in any desirable manner. At the same point or at a different point in the material advance other transverse fold 115 lines or creases 32 are formed which extend between the longitudinal fold lines. Also at a suitable point in the material movement longitudinal cuts are made to sever portions 120 of the continuous assembly which will con- 125

stitute corner laps and end wings in the individual blanks, when severed and these cuts may be simple slits, or as desirable in some cases, they may be in the form of narrow strips of material excised from the composite blank, producing slots 40 which may be substantially commensurate in width with the spaces 8 between shell strips 4 and 5, and directly in line with them, or if necessary or desirable these slots may be somewhat wider.

The combined materials are then severed at regular intervals on a transverse line 45 and for a box blank of the particular form in view, coincidental with this severing, or before or afterward, rectangular portions are excised from the sides of the blank co-extensive with the outer shell strips 5, these excised portions being represented by the rectangular spaces 47, Figures 3 and 4.

There is thus produced an individual box forming blank or assembly B, Figures 3, 4 and 10, comprising a central or body section *a*, side wings *b*, corner laps *c* extending from ends of the side wings, end wings *d*, and end wing extensions or margins *e*, each of these portions consisting of both shell and cover material. The parts *a*—*d*—*e*, and *b*—*c* of the shell material are of course initially disconnected by the severing operation previously described, but are reconnected by the hinge strips, portions 12^a and 12^b of which extend alongside the slits or slots 40 to the ends of the blank between the shell material and cover paper.

The blank is now folded in one or more stages or series of operations, the intermediate operations being sufficiently explained in Figures 7, 9 and 11. In folding, the side portions of the blank, that is, the members *b*—*c*, are turned at right-angle to the central portions, producing the hinge or corner folds such as that shown in Figure 7, or Figure 9. It is evident from these figures showing the approximate position of the materials along the longitudinal corner folds, that the shell material is, in the folding operation, free to move without distortion, all the bending taking place in the hinge strip and the cover strip, which are relatively thin and flexible and can therefore bend easily to make a smooth fold without any appreciable strain in those materials and of course without any tendency to crack or break. Although not necessary in all cases, the folding and forming operations are usually performed over a plunger or "form," and the shell portions 4 and 5 may therefore be accurately located in relation to each other. Since they do not really take any part in the bending operation, it is evident that there is no tendency to distort or strain the shell materials, and therefore in the completed box these parts including the side walls consisting of the blank members *b*, remain perfectly smooth

and flat and no special precautions are required to remove bulges or to prevent the occurrence of bulges during the process, and especially in the steps of folding the blank into box form.

The corner laps *c* are then turned in, the end wings *d* are turned up and the end wing extensions *e* are turned in and secured to inner margins of the corner laps, adhesive being supplied to suitable parts of the blank at any suitable stage of the proceedings, for instance, adhesive may be supplied to inner surfaces of the assembly end wings and end wing extensions *d* and *e* while the materials are still in continuous assembly form or after the individual blanks are severed, and in fact at any time before the end-wing and end-wing-extension-surfaces are brought in contact with the shell surfaces. The end structure is then pressed in position, producing a completed box part, shown in Figure 12, in which all external surfaces are covered by the cover paper, all the wall edges are covered by over-turned portions of the cover paper, and in this particular example, the only part of the shell material visible is along the shell edges 50, Figure 12. By suitable additional expedients or precautions in the process as sufficiently explained in previous applications, and especially in my companion applications above referred to, provision may be made for covering all of the shell material including all edges along lines 50 and elsewhere.

A box produced in the present instance is very strong and durable, especially in view of the reinforced ends or end margins, and particularly in view of the heavy edge reinforcements provided by the in-turned end wing extensions *e*, consisting of combined shell and cover material and including also portions 12^a of the hinge strips. The end structure is further reinforced by hinge strip portions which are in-turned against the inner faces of the end wings *d*.

Figure 5 illustrates a variation in initial stages of the process which is desirable in some cases. In this example the shell strips 4^a and 5^a are furnished in the form of originally separate rolls 4^b and 5^b. This affords an opportunity for economy in material, since in a box factory or other paper-working establishment strips of box forming material such as card board or chip board, or other suitable box body forming material, are frequently available as trimmings, and these trimmings may be cut to accurate width and rolled up to provide any of the rolls 4^b and 5^b, Figure 5. Frequently the outer rolls 5^b, even in boxes of rather large central dimensions, may be quite narrow, as in the case of producing box covers with shallow walls, and of course in smaller sizes of boxes materials may often be available in proper widths for any of the box-forming

4
web strips. Regardless of the question of cost of material, it may be desirable, in some cases, to provide the shell strips in originally separate form, and evidently by such provision the slitting and separating operations may be avoided.

The strips pass over a guide roll 7 as in the previous instance, and are properly spaced, or maintained in properly spaced 10 alignment, by any suitable spacers or separators, such as 9^a, and from that point on the operations may be substantially the same as in the previous example, including the application of the adhesively conditioned hinge 15 or connecting strips, the cover web and so on.

I claim:

1. A method of producing box blanks, comprising concurrently advancing two or more strips of box forming material, applying connecting strips to secure the first named strips together, applying and securing a cover sheet and severing the continuous assembly so produced at regular intervals to form individual box blanks.
2. A method of producing box blanks comprising advancing two or more strips of box forming material in substantially parallel relation, applying connecting strips to secure the first named strips together, applying a cover sheet adhesively over the connecting strips and severing the continuous assembly so produced at regular intervals to form individual box blanks.
3. A method of producing box blanks, comprising advancing a plurality of strips of box-board in substantially parallel relation, advancing connecting strips of sheet material and adhesively securing them to adjacent margins of the board strips to form hinge or fold connections, applying a continuous web of sheet cover material adhesively to the board strips over the hinge strips, and severing the continuous assembly so produced at regular intervals to form individual box blanks.
4. A method of producing box blanks, comprising advancing a plurality of strips of box-board in substantially parallel relation, advancing connecting strips of sheet material and adhesively securing them to adjacent margins of the board strips to form hinge or fold connections, depressing the connecting strip material between adjacent edges of the board strips, applying a continuous web of sheet cover material adhesively to the board strips over the hinge strips, and severing the continuous assembly so produced at regular intervals to form individual box blanks.
5. A method of producing box blanks, comprising advancing a plurality of strips of box-board in substantially parallel relation, spacing adjacent edges of the different strips a suitable distance apart, advancing connecting strips of sheet material and ad-

hesively securing them to adjacent margins of the board strips to form hinge or fold connections, applying a continuous web of sheet cover material adhesively to the board strips over the hinge strips, and severing the 70 continuous assembly so produced at regular intervals to form individual box blanks.

6. A method of producing box blanks, comprising advancing a plurality of strips of box-board in substantially parallel relation, spacing adjacent edges of the different strips a suitable distance apart, advancing connecting strips of sheet material and adhesively securing them to adjacent margins of the board strips to form hinge or fold 80 connections, depressing the connecting strip material between adjacent edges of the board strips, applying a continuous web of sheet cover material adhesively to the board strips over the hinge strips, and severing the continuous assembly so produced at regular intervals to form individual box blanks.

7. A method of producing box blanks, comprising advancing a plurality of separate strips or webs of box shell material in 90 substantially parallel relation, spacing adjacent edges of the strips apart a suitable distance with regard to the fold to be produced, advancing hinge strips and adhesively affixing one of the strips over the space between each two adjacent shell strips in contact with the shell strip margins, advancing a continuous web of cover material and adhesively securing it to the surface of the combined shell webs over the hinge strips, 100 and severing the assembly transversely at regular intervals to produce individual box blanks.

8. A method of producing box blanks, comprising advancing a continuous web of 105 box shell or body material, slitting the web longitudinally into a plurality of parts, applying continuous strips of flexible sheet material to reconnect the parts, and severing the continuous assembly so produced at regular intervals to form individual box blanks.

9. A method of producing box blanks, comprising advancing a continuous web of box shell or body material, slitting the web longitudinally into a plurality of parts, applying continuous strips of flexible sheet material to reconnect the parts, advancing a continuous web of cover material and adhesively securing it to a face of the reconnected shell web over the connecting strips, 120 and severing the continuous assembly so produced at regular intervals to form individual box blanks.

10. A method of producing box blanks, comprising advancing a continuous web of 125 box shell or body material, slitting the web longitudinally into a plurality of parts, reconnecting the parts by adhesively applying continuous strips of flexible sheet material, and severing the continuous assembly 130

so produced at regular intervals to form individual box blanks.

11. A method of producing box blanks comprising advancing a continuous unitary web of box-board or shell material, splitting the web longitudinally along a plurality of lines to separate it into strips, spacing the strips slightly apart, advancing continuous strips of flexible hinge material corresponding to the divisions in the shell web and applying the hinge strips adhesively to reconnect the shell strip, applying a continuous web of cover paper to a surface of the reconnected shell web over the hinge strip, and severing the assembly transversely at regular intervals to produce individual box blanks.

12. A method of producing boxes, comprising concurrently advancing two or more strips of box forming material, applying connecting strips to secure the first named strips together, applying and securing a cover sheet, severing the continuous assembly so produced at regular intervals to form individual box blanks, and folding and securing the individual blanks in box form.

13. A method of producing boxes, comprising advancing a plurality of strips of box-board in substantially parallel relation, advancing connecting strips of sheet material and adhesively securing them to adjacent margins of the board strips to form hinge or fold connections, applying a continuous web of sheet cover material adhesively to the board strips over the hinge strips, severing the continuous assembly so produced at regular intervals to form individual box blanks, and folding and securing the individual blanks in box form.

14. A method of producing boxes, comprising advancing a plurality of separate strips or webs of box shell material in substantially parallel relation, spacing adjacent edges of the strips apart a suitable distance with regard to the fold to be produced, advancing hinge strips and adhesively affixing one of the strips over the space between each two adjacent shell strips in contact with the shell strip margins, advancing a continuous web of cover material and adhesively securing it to the surface of the combined shell webs over the hinge strips, severing the assembly transversely at regular intervals to produce individual box blanks, and folding and securing the individual blanks in box form.

15. A method of producing boxes, comprising advancing a continuous web of box shell or body material, slitting the web longitudinally into a plurality of parts, applying continuous strips of flexible sheet material to reconnect the parts, severing the continuous assembly so produced at regular

intervals to form individual box blanks, and folding and securing the individual blanks in box form.

16. A method of producing boxes, comprising advancing a continuous web of box shell or body material, slitting the web longitudinally into a plurality of parts, applying continuous strips of flexible sheet material to reconnect the parts, advancing a continuous web of cover material and adhesively securing it to a face of the reconnected shell web over the connecting strips, severing the continuous assembly so produced at regular intervals to form individual box blanks, and folding and securing the individual blanks in box form.

17. A method of producing box blanks, comprising concurrently advancing a plurality of strips of box-material, applying and securing another layer of material to connect the strips in foldable relation, and forming individual box blanks from the continuous assembly thus produced.

18. A method of producing box blanks, comprising concurrently advancing a plurality of strips of box-material in slightly spaced relation, applying sheet material adhesively to the strips across the spaces to retain the strips in foldable relation, and forming individual box blanks from the continuous assembly so produced.

19. A method of producing box blanks, comprising concurrently advancing a plurality of strips of box-material, adhesively applying sheet material to connect the strips in foldable relation, applying other sheet material as reinforcing and covering material, and forming individual box blanks from the continuous assembly so produced.

20. A method of producing box blanks, comprising concurrently advancing a plurality of strips of box-material, applying and securing another layer of material to hold the strips in predetermined relation, depressing said other layer of material between adjacent edges of the strips, and forming individual box blanks from the continuous assembly so produced.

21. A method of producing box blanks, comprising concurrently advancing a plurality of strips of box-material, applying and securing another layer of material to hold the strips in predetermined relation, depressing said other layer of material between adjacent edges of the strips to form beaded folding lines, and forming individual box blanks from the continuous assembly so produced.

Signed at New York city in the county of New York and State of New York, this 20th day of December, A. D. 1922.

HARRY BRIDGMAN SMITH.
